CRIMPING APPARATUS

**Daniel D. Huyett, Wilmington, Del., assignor to
Atlas Powder Company, Wilmington, Del., a
corporation of Delaware**

Application September 14, 1946, Serial No. 697,142

12 Claims. (Cl. 153—73)

1

This application relates to methods and apparatuses for crimping shells.

An object of the invention is the provision of methods and apparatuses for crimping shells without undue weakening of the shell surfaces.

Another object of the invention is the provision of methods and apparatuses for crimping shells evenly and uniformly.

A further object of the invention is the provision of methods and apparatuses for crimping a number of shells at a time.

Other objects of the invention will be apparent from the following description.

Crimping is an important operation in many manufacturing processes, such as in the manufacture of ammunition and in the sealing of metal explosion initiators such as blasting caps and squibs.

Crimping methods have included squeezing shells between dies, spinning shell metal, and swaging operations. Most of these crimping techniques, however, have been slow and cumbersome in operation and have produced uneven crimps or have resulted in serious weakening of crimps through undue thinning of shell walls.

A further disadvantage of most methods and apparatuses for crimping shells is that they are not adaptable to crimping a plurality of shells which are held closely together.

According to the present invention, methods and apparatuses are provided by means of which shells may be crimped rapidly and uniformly without excessive weakening or thinning of the shell walls, and the present methods and apparatuses are particularly well adapted to the simultaneous crimping of large numbers of closely spaced shells.

The present invention is accomplished by translating a concave crimping edge relative to 40 a shell and against a shell in a path generally similar to the crimping edge.

The invention will be further described in connection with the drawings which show apparatuses for crimping shells of electric explosion initiators and in which:

Figure 1 is a side view partly in section of a specific embodiment of an apparatus for performing the invention.

Figure 2 is a top view partly in section of the apparatus shown in Figure 1.

Figure 3 is a partial end view partly in section of the apparatus of Figure 1.

Figure 4 is an enlarged detail of a crimping edge of the apparatus shown in Figure 1.

2

Figure 5 is a side view partly in section of a modified apparatus for performing the invention.

Figure 6 is a top view partly in section of the apparatus of Figure 5.

Figure 7 is a diagrammatic representation of the action produced by the apparatus of Figure 1.

Figure 8 is a diagrammatic representation of the action produced by the apparatus of Figure 4.

Figure 9 is an enlarged sectional view showing a modified crimping edge.

Figure 10 is an enlarged sectional view of another type of crimping edge, and

Figure 11 is an enlarged sectional view of a modified mounting for a crimping edge.

Referring to Figures 1, 2, and 3 of the drawings which show apparatus for crimping two blasting caps, the apparatus is made up first of a cast support member 20 which may be attached in any convenient manner (not shown) to a wall or a table. Support member 20 is provided with two wells 22 and 24 dimensioned to receive blasting caps 26 and 28. Journaled in support member 20 are rotatable shafts 30 and 32. In the operation of the apparatus shaft 32 is driven by crank

34 and has keyed to it gear 36. Gear 36 drives idling gear 38 which rotates freely on shaft 40 screwed into support 20. Idling gear 38 in turn drives gear 41 of the same size as gear 36, which is carried by and drives shaft 30. Shafts 30 and

32 are enlarged and hollowed out at their top portions to form yokes 42 and 44. Each of yokes 42 and 44 support similar parts which are shown in section, for yoke 42, in Figures 2 and 3. Because of the similarity of parts, the further description of these portions of the apparatus will, for convenience, be made only in connection with yoke 42. Through yoke 42 is journaled rotatable shaft 46. Shaft 45 is threaded on its portions inside yoke 42 and on one end is keyed to sprocket wheel 48. Sprocket wheel 48 bears on its face eight pins 50. Affixed to support 20 is finger 52 in position to engage the lowermost of pins 50.

Inside yoke 42 and in threaded engagement with shaft 46 is block 54. Block 56 in sliding engagement with the top of yoke 42 is integral with block 54 and also with shaft 58 extending from its upper portion. Shaft 58 and its corresponding member 60 on the opposite side of the apparatus are journaled in plate or jig 62. Washers 63 and

64 and nuts 65 and 66 form hubs over plate 62 on shafts 58 and 60. Plate 62 is provided with two circular crimping edges 67 and 68 around caps 26 and 28, respectively. Over plate 62 is positioned cover plate 69 which is secured to support

55 20 by screws 70. It is to be noted that support 20

is recessed to provide space for crimping plate 62. Cover plate 69 is provided with holes 71 and 72 permitting passage of blasting caps 26 and 28.

In the position in which the apparatus is shown in the drawings, block 54 is off to the side of yoke 42 next to sprocket 48, and shaft 58 rotates on the same center as shaft 30. It may be seen, however, that if shaft 46 is rotated to the left, block 54, as shown in Figure 3, will move to the right (or up in Figure 2) and will carry with it shaft 58 so that then as shaft 30 turns shaft 58 becomes a crank pin describing a circle around the center line of shaft 30. If both shaft 58 and shaft 60 have been moved the same amount, plate 62 on rotation of shafts 32 and 30 will be translated in circular motion.

Sprocket wheel 48 and its counterpart on the opposite side of the apparatus provide means for uniformly changing the positions of shafts 58 and 60. As with the description of the parts connected with shafts 58 and 60, the operation will only be described in connection with sprocket 48 turning with shaft 30, though it will be understood that the operation of the parts turning with shaft 32 is similar. As shaft 30 is turned, sprocket wheel 48 turns around the center line of shaft 30. With this action the lowermost of pins 50 pushes against stationary finger 52 so that the sprocket 48 is rotated until the pin in contact with finger 52 clears the top of finger 52 thereby bringing the adjacent pin 50 into lowermost position. After sprocket 48 has been thus partially rotated, it continues to be carried round by shaft 30 until it again reaches a forward position and the now lowermost pin 50 is in position to be pushed by finger 52, rotating sprocket 48 a further increment. Thus each time shaft 30 turns, sprocket 48 makes a partial rotation and block 54 threaded to shaft 46 moves a distance along shaft 46. Since shaft 58 is integral with block 54, the center line of shaft 58 moves a distance way from the center line of shaft 30 as block 54 moves along shaft 46. Thus the center line of shaft 58, from a position such that it coincides with the center line of shaft 30, is moved a distance away from the center line of shaft 30, then makes approximately one revolution around that center line, is moved another increment away from the center of shaft 30, makes approximately another revolution around that center line, and this action is repeated. Expressed in another way, shafts 58 and 60 may be considered as crank pins, the crank arms of which vary by increments once each revolution, and consequently plate 62 is translated in ever wider circles. The effect of this translation is gradually to force crimping circles 67 and 68 first against and then into and around shells 26 and 28, respectively, thus performing the crimping operation. In Figure 4 is shown the manner in which crimping edge 67 impinges upon cap 26 to produce a crimp. When the crimp has been finished, the operation of the apparatus is reversed until the center lines of shafts 58 and 60 again coincide with the center lines of shafts 30 and 32 and the crimped shells are withdrawn.

In Figure 7 is shown diagrammatically the path of translation of the crimping plate and crimping edge. At the left of the figure is shown the shape of the path taken by each of shafts 58 and 60 and also by each point in the plate 62. At the right hand side of the figure is shown how one point on the crimping edge pushes into the shell on each circuit of the crimping plate

until the crimp has been completed. Every point on the crimping edge takes a similar path and does its work in deforming the shell. It is to be noted that there is very little sliding action of the crimping edge on the shell. Most of the crimping action takes place by direct pushing of the crimping edge into the shell. As a result of this pushing action, there is very little thinning of the metal of the shell and resultant 10 weakening of the shell walls at point of crimping. It will also be noted that the shell is pushed in an equal amount from all sides and that an even crimp is produced.

The crimping apparatus just described forms the crimp by a step-wise action in that the crimping edge moves in and then is translated in rotary motion around the shell, the crimping edge again moves in and is again translated in rotary motion and so on.

In Figures 5 and 6 is shown a modified apparatus in which the inward motion of the crimping edge is continuous as the crimp is formed. In Figures 5 and 6 parts similar to those shown in Figures 1, 2, 3, and 4 are given similar numbers. Support members 20 in addition to having shafts 30 and 32 journaled in it also contains journaled therein shafts 74 and 76. Shafts 74 and 76 have on their lower ends same size gears 78 and 80, respectively, which 25 mesh with gears 41 and 36. On their upper ends shafts 74 and 76 are provided with same size gears 82 and 84 which are slightly smaller than gears 78 and 80. Idling on shaft 30 is compound gear 86 which is provided with spur gear portion 30 35 88 and bevelled gear portion 90. Gear 82 meshes with and drives spur gear portion 88. Bevelled gear portion 90 drives bevelled gear 92 which is the same size as gear portion 90 and is keyed to shaft 46. On the opposite side of the 40 apparatus spur gear 84 drives the counterpart of shaft 46 through a similar train of gears. The remaining parts of the apparatus are quite the same as those of Figures 1, 2, and 3. Since gear 82 is slightly smaller than gear 78, as crank 45 34 is turned and shaft 30 is driven through gears 36, 38, and 41, gear 86 idling on shaft 30 turns at a slightly slower rate than does shaft 30. Therefore, gear 92 which is driven by gear 86 makes a partial rotation each time it is carried 50 around shaft 30. Thus, as handle 34 is turned and the machine is operated, shafts 58 and 60 make a spiral motion proceeding outwardly from the center points of shafts 30 and 32, respectively. Plate 62 is translated in the same manner and each point on it makes the same spiral motion, as is diagrammatically shown in Figure 8.

Since each point on plate 62 moves in a spiral, each point on the crimping edge moves in a spiral and each point on the crimping edge is gradually pushed into the shell to form the crimp.

After the crimp has been made, crank 34 is rotated in an opposite direction until the shell 65 may be freed and withdrawn from the apparatus.

The motion produced by the apparatus described may be explained in another way. While the shell is in a fixed position, the circular crimping edge which might be called a die is placed 70 against the shell. It is then uniformly moved or translated in a generally circular movement of increasing diameter, the initial diameter being the difference between the diameter of the crimping edge and the diameter of the shell, and

the final diameter being that difference plus twice the depth of the crimp, though this depth of crimp is somewhat lessened by any movement of the shell in its holding means and any springing of the shell away from the crimping edge. An entirely satisfactory crimp is obtained when a 0.276 inch diameter shell is placed in a 0.283 diameter support and crimped with a 0.290 inch diameter crimping edge when the crimping edge moves in circles the largest of which has a diameter of 0.140 inch.

As is shown in Figures 1, 4, and 5 the crimping edge is constructed to provide two crimps in the shell. It may be readily seen that the edge may be constructed to form a single crimp or to form any multiplicity of crimps. Figure 9 shows a shell 26 being crimped around a plug 94 containing leg wires 96 and 98 passing through it in conventional manner. The crimping edge in crimping plate 62 is constructed to provide two crimps and also to turn over the top of shell 26.

In place of a single crimping plate, a multiplicity of crimping plates may be driven in the manner described. This is shown in Figure 10 wherein plates 100, 102, and 104 are all driven to act on the cap while plates 106 and 108 remain stationary. Plates 100, 102, and 104 may, of course, be driven by shafts common to all of them. In the modifications shown in Figure 9 and Figure 10, there is no top plate on which the cap bears, such as is shown in Figure 4.

While the crimping operations just described function primarily due to a pushing action on the shell rather than a sliding action, there is a small amount of sliding brought about by virtue of the difference in diameters between the crimping edge and the shell being crimped. In each circuit each point on the crimping edge must act against the cap shell. Hence in one circuit of the edge about the shell the longer crimping edge must slide a bit on the shorter shell circumference. This small slippage may be minimized by mounting the crimping edge in the crimping plate so that it is free to turn. Thus as shown in Figure 11 crimping edge 67 is mounted in plate 62 by conventional circular ball bearing made up of balls 110 and retainer ring 112. With the crimping edge rotatably mounted, the tendency of the edge to slip on the shell being crimped is resisted and the ring instead tends to roll on the shell. Thus each circuit around the shell somewhat less than the entire circumference of the crimping edge contacts the shell.

While the methods and apparatuses have been described in connection with circular crimps on circular shells, it may be seen that shells and crimps of other peripheral shapes such as oval shapes, for example, may be employed providing that the crimping edge has a concave contour along its length, and that the crimping plate is moved in a path, generally similar to the shape of the crimp desired.

Also while the method and apparatuses have been described for a stationary shell and a moving crimping plate, it will be understood, of course, that it is only important that the proper relativity of motion be maintained between the shell and the crimping plate. Thus the crimping plate may be held stationary and the shell may be moved if desired.

One principal advantage of the present invention is its applicability to the crimping of a number of shells at a time. While the specific

apparatuses described above show the crimping of two shells at one time, it is readily seen that since each point on the crimping plate moves through a similar path, numerous crimping edges may be included in the crimping plate and on very close centers.

What is claimed is:

1. Apparatus for crimping shells comprising means for holding a shell, a crimping edge having a concave contour along its length, a member containing said edge, two driving elements mounted in said member, means for moving said elements so as to bear said edge against said shell, and means for moving said elements in separate congruent paths generally similar to said edge whereby said member is translated in a path generally similar to said edge.
2. Apparatus for crimping shells comprising a means for holding a shell, a crimping edge having a concave contour along its length similar to the circumference of the crimp desired in said shell, a member containing said edge, two driving elements mounted in said member, means for moving said elements so as to bear said edge against said shell, and means for moving said elements in separate congruent paths generally similar to said edge whereby said member is translated in a path generally similar to said edge.
3. Apparatus for crimping circular shells comprising means for holding a shell, a circular crimping edge having a concave contour along its length, a member containing said edge, two driving elements mounted in said member, means for moving said elements so as to bear said edge against said shell and means for moving said elements in separate congruent rotary paths.
4. Apparatus for crimping circular shells comprising means for holding a shell, a circular crimping edge having a concave contour along its length, a member containing said crimping edge, two driving elements mounted in said member, means for moving said elements so as to bear said edge against said shell, and means for simultaneously moving said elements in separate congruent rotary paths of increasing radius.
5. Apparatus for crimping circular shells which comprises means for holding a shell, a circular crimping edge having a concave contour along its length, a member containing said crimping edge, two driving elements mounted in said member, means for moving said elements so as to bear said edge against said shell, and means for simultaneously moving said elements in separate congruent circular paths of variable radius.
6. Apparatus for crimping shells comprising means for holding a shell, a circular crimping edge having a concave contour along its length, a member containing said edge, two driving elements mounted in said member, means for moving said elements so as to bear said edge against said shell, and means for simultaneously moving said pins in separate congruent spiral paths of increasing radius.
7. Apparatus for crimping circular shells comprising means for holding a plurality of shells in spaced relation, a plate containing a plurality of circular crimping edges spaced to encircle said shells, two pins each rotatably mounted in said plate, means for revolving each of said pins about a separate point and means for varying the radius of gyration of each of said pins about the point around which it revolves, whereby said plate is translated through a rotary path and said edges crimp said shells.
8. Apparatus for crimping shells comprising

means for holding a plurality of shells in spaced relation, a plate containing a plurality of spaced circular crimping edges positioned to encircle said shells, two cranks the pins of which are rotatably mounted in said plate, means for rotating the shafts of said cranks and means for varying the lengths of the arms of said cranks whereby said plate is translated through a rotary path and said edges crimp said shells.

9. Apparatus for crimping shells comprising means for holding in spaced relation a plurality of shells of similar cross section, a member containing a plurality of crimping edges having concave contours along their lengths and spaced to enclose said shells individually, means for simultaneously pressing said edges against said shells and translating said member, without angular change in the position of said member, relative to said shells in paths generally similar to said edges.

10. Apparatus for crimping shells comprising means for holding in spaced relation a plurality of shells of similar cross section, a member containing a plurality of crimping edges concave along their lengths similar to the circumference 25 of the crimps desired in said shells, said edges being spaced to enclose said shells individually, means for simultaneously pressing said edges against said shells and translating said member, without angular change in the position of said 30 member, relative to said shells in paths generally similar to said edges.

11. Apparatus for crimping shells comprising

means for holding in spaced relation a plurality of shells of circular cross section, a member containing a plurality of circular crimping edges said edges being spaced to enclose said shells individually, means for simultaneously pressing said edges against said shells and translating said member, without angular change in the position of said member, in circular paths of different radius.

12. Apparatus for crimping shells comprising means for holding a plurality of circular shells, a member containing a plurality of circular crimping edges positioned to encircle said shells individually, means for simultaneously pressing said edges against said shells and translating said member, without angular change in the position of said member, in a spiral path of increasing radius.
